[57] ABSTRACT

A telescopic crane jib of the kind comprising individual telescopic parts which have means by which they are locked together when they are telescopically extended is provided with a mechanism for extending and retracting the parts and this mechanism is capable of operation with the jib in a vertical position so that it is not subjected to any bending moments owing to its own weight during extension. This enables an overlap between the telescopic parts to be avoided and the locking means are arranged to lock the parts together end to end. A jib housing surrounds the telescopic parts when they are in their retracted positions and this housing is at least twice as long as each of the telescopic parts. The housing has at its upper end a releasable catch device which is operative to hold a telescopic part in position above the housing after it has been extended from within the housing and this extension is preferably effected by a single-acting hydraulic cylinder which is fixed to the lowest telescopic part and has a piston extending downwards from it and acting on the bottom of the housing.

TELESCOPIC CRANE JIB

This is a Continuation-in-Part of application Ser. No. 225,566 filed Feb. 11, 1972, now abandoned.

This invention relates to telescopic crane jibs the individual telescopic parts of which are positively locked together, for example by bolts, after the jib has been extended.

Existing telescopic crane jibs have the considerable disadvantage that the full length of each telescopic part cannot be utilised in extending the jib because the jib is being extended it is usually either horizontal or nearly so. With the jib in this position the comparatively heavy, telescopic parts overlap or interfit for a substantial length to enable them to withstand the bending moments induced in them owing to their horizontal attitude until they have been locked together. Even so the bending stresses due to the weight of the jib may alone be sufficient to damage the telescopic parts where they come into contact with each other at the overlap before locking.

The object of the present invention is to provide a telescopic crane jib in which substantially the full lengths of the individual telescopic parts are utilised. The jib may also be lighter in weight and easier to set up and extend than conventional telescopic jibs.

To this end according to this invention, a telescopic crane jib comprises individual telescopic parts which have locking means by which they are positively locked together when they are telescopically extended and means capable of extending and retracting the parts with the longitudinal axis of the jib at least substantially vertical, the locking means being situated at the ends of the telescopic parts and being arranged to lock the parts together end to end.

When the jib is at least substantially vertical, the individual telescopic parts are in stable, balanced positions and consequently bending moments do not occur to any great extent. Under these circumstances the individual telescopic parts can be extended to their full lengths end to end. A further advantage obtained is that no additional structural parts are necessary for guiding the telescopic parts during the extension of the jib. Consequently it is possible to use telescopic parts of kinds which are unsuitable for use in conventional telescopic jibs because they are difficult to guide and, in conventional jibs, require the use of additional guiding parts. In particular various lattice frame constructions can now be used.

According to a preferred feature of the invention, there is a jib housing which surrounds the telescopic parts when they are in their retracted positions, the housing being at least twice as long as each telescopic part and having at its upper end releasable catch means for holding a telescopic part in position after it has been extended from within the housing by the extending and retracting means.

This arrangement makes it possible to utilise the weight of the telescopic part for facilitating the retracting operation. When the jib is being extended all the telescopic parts are lifted together until the releasable catch means engages with the telescopic part which is the next to be extended, whereupon the other telescopic parts, nested together, are allowed to move downwards again. The telescopic part which is retained by the catch means remains suspended from the top of the housing so that this telescopic part is extracted

from within the other parts. The other telescopic parts continue to move downwards, under gravity until they reach their lowermost positions in the housing.

The extending and retracting means preferably comprises a single-acting fluid pressure-operated cylinder fixed to the lowest telescopic part and having a piston extending downwards from it. This enables it to lift all the telescopic parts simultaneously. The telescopic parts are nested together, the one within the other, so that they support each other.

The upward thrust which the cylinder has to apply in lifting the telescopic parts can be reduced by using telescopic parts of lattice frame construction. Furthermore the work which the cylinder has to do can be reduced by attaching a head-stay cable to the head of the jib. The head-stay cable reduces the bending load on the jib when the jib is supporting a working load. This allows the telescopic parts of the jib to be of lighter and less costly construction.

The extension of the telescopic parts to their full lengths is facilitated in accordance with a further feature of the invention, by making the internal cross section of the upper end of each telescopic part smaller than the external cross section of the lower end of the telescopic part within it. During the extension of the jib this prevents the extended telescopic parts from becoming detached from the remaining telescopic parts, which are still nested together. The arrangement also simplifies the control of the fluid pressure-operated cylinder. To provide the telescopic parts with the required cross section sizes at their upper and lower ends, each telescopic part may have, at its upper end, one or more inwardly directed limit stops to limit the telescopic extension of the part within it. When the jib is being extended the limit stop or stops locate the telescopic parts accurately in position relative to each other, irrespective of slight inaccuracies in the applied movements. Preferably, there are a number of oppositely situated pairs of limit stops. This prevents the telescopic parts from assuming tilted attitudes relative to each other.

Each telescopic part is preferably of square or other rectangular cross section, the cross section being decreased at the top and increased at the lower end.

Preferably, the locking means are arranged to operate in two stages, the locking means transmitting compressive forces after operation of the first stage and tensile forces as well after operation of the second stage.

Each locking device may comprise two bolts and a support, the two bolts being positioned in line with each other and being slidable in directions perpendicular to the longitudinal axis of the jib, the two bolts sliding in opposite directions in two adjacent telescopic parts in such a way that when the one bolt has been advanced the two bolts are accurately aligned with each other by the support and advancement of the other bolt causes the two bolts to engage with each other.

The support may be fixed to one of the adjacent telescopic parts, or can form a part of the telescopic part itself, if desired projecting from it. The support preferably has an opening which corresponds to the cross-section of the bolt of the adjacent telescopic part and is in line, in the direction of the longitudinal axis of the jib, with this bolt, so that when this bolt has been advanced into its locking position and the telescopic part moves downwards relative to the support, the bolt comes to rest on the support.

The bolt which cooperates with the support may have an opening in which the other bolt engages when it is advanced in the direction of the first bolt in the second stage of the locking operation.

The opening in the first bolt may for example be a central bore and the other bolt has a projection on its end facing the first bolt, the projection being arranged to engage in the bore when the centres of the two bolts are equidistant from the support. The two bolts of the locking device are preferably actuated by fluid pressure-operated cylinders. The bolts may be provided with auxiliary safety devices which can for example be manually actuated. Means may be provided for delivering a warning signal if the safety devices are not engaged. Operation of the safety devices causes the signal to cease.

Locking devices mounted at the ends of the individual telescopic parts are preferably also capable of locking the telescopic parts to the housing when they are nested within the housing. The telescopic parts may then be locked at both their upper and lower ends. For this purpose the locking bolts may engage in sleeves or openings in the telescopic parts and in the jib housing, the sleeves or openings having wedge surfaces for compensating for manufacturing tolerances in the distances between the locking means at the upper and lower ends of the telescopic parts.

The lock may be made safe by a wedging device which may comprise thrust pins which move perpendicular to the longitudinal axes of the bolts, each thrust pin being thrust against its bolt by fluid pressure-operated cylinders acting through a wedge.

When the telescopic parts are nested together they may be locked to each other at both ends by means of locking bolts which have wedge surfaces or the like cooperating with corresponding wedge surfaces in the openings. This arrangement has the advantage that a firm connection without free play is obtained even if the distances between the locking devices vary by a few millimetres due to manufacturing tolerances.

The locking bolts preferably lie on the diagonals of the jib cross section. This is to ensure that no torsional moments about the longitudinal axis of the jib can be transmitted to the fluid pressure-operated cylinder or other extending and retracting means.

The releasable catch means fixed to the jib housing may comprise a number of spring loaded catches or gravity loaded catches, arranged so that they can be released, either by hand or by means of fluid pressure-operated cylinders or by means of levers. When the catches are released the telescopic parts are lowered by gravity.

A jib in accordance with the invention may also include a telescopic part which forms a telescopic peak jib. Such a jib can be constructed as described above. The peak jib can be the innermost telescopic part of a main jib, being extended from and retracted into the jib housing with the other telescopic parts. On the other hand if desired the peak jib can be in the form of a telescopic part which opens apart in halves when the jib is extended.

Two examples of crane jibs in accordance with the invention are illustrated in the accompanying drawings, in which:

FIG. 1 is a diagrammatic longitudinal section through a first example showing the parts telescoped together;

FIG. 2 is a cross section taken along the line II—II in FIG. 1;

FIG. 3 is a cross section taken along the line III—III in FIG. 1;

FIGS. 4, 4a, 4b, 5, 6 and 7 show the crane jib shown in FIG. 1 in several different stages of extension;

FIG. 8 shows a device for locking together the telescopic parts of the crane jib shown in FIG. 1;

FIG. 8a is a cross section taken along the line VIIIa—VIIIa in FIG. 8;

FIG. 8b is a cross section taken along the line VIIIb—VIIIb in FIG. 8;

FIG. 8c is a view similar to FIG. 8 illustrating a warning arrangement for the locking device;

FIG. 8d is a schematic showing of the control system for the warning arrangement shown in FIG. 8c;

FIG. 9 is a section taken along the line IX—IX in FIG. 8;

FIGS. 10, 11 and 11a show further examples of locking devices for locking together the telescopic parts of the crane jib shown in FIG. 1;

FIG. 12 shows the crane jib shown in FIGS. 1 to 11a incorporated as part of a mobile crane, the remainder of which is shown only diagrammatically; and

FIG. 13 shows a second example.

The telescopic crane jib shown in FIG. 1 has a jib housing 1 and three telescopic parts 2, 3, 4. As shown in FIGS. 2 and 3 each telescopic part in square in cross section corresponding to the square cross section of the jib housing 1. Both the housing and the telescopic parts are of lattice frame construction with tubular frame members.

In addition to the telescopic parts 2, 3 and 4 the crane jib also has short peak outriggers 5 and 6. FIGS. 1, 4, 4a and 4b are longitudinal sections taken along a diagonal of the housing and telescopic sections. When the crane jib is being telescopically extended or retracted the movements of the telescopic parts, that is to say the parts 2, 3, 4 and the peak outriggers 5, 6, are all moved by a single hydraulic cylinder 8, which is single-acting. The bottom of the cylinder 8 is fixed rigidly to the lowest telescopic part 2. A piston rod 7 of the hydraulic cylinder has its lower end fixed to the bottom of the jib housing 1. The lowest telescopic part 2 is guided in its telescoping movements by rollers 9 which roll along rails 10 of the jib housing 1. When the lowest telescopic part 2 is moving upwards in the jib housing 1 it carries upwards with it the other two telescopic parts 3 and 4 and the peak outriggers 5, 6, because bases 11, 12, 13 of these parts are supported on a base 14 of the lowest telescopic part 2.

The three telescopic parts 2, 3 and 4 are all of the same length. This length is less than half the length of the jib housing 1. When the crane jib has a vertical attitude, as shown in FIG. 1, the jib is extended telescopically by repeated strokes of the cylinder 8, that is to say it is extended in several stages, each extension movement being terminated by a locking together of the individual telescopic parts 2, 3, 4 and of the peak outriggers 5 and 6.

The telescopic extension of the jib is effected as follows: First of all the jib is brought to a vertical attitude, as shown in FIG. 1, by means of a head-stay cable 25 and a retraction mechanism acting on the cable. The jib is locked in the vertical attitude by a telescopic rod device 26. When this has been done the cable can be slackened. In the next stage of the operation, starting

with the parts in the positions shown in FIG. 1, hydraulic liquid is exhausted from the cylinder 8. Consequently the three telescopic parts 2, 3, 4 all move downwards together in the jib housing 1, leaving the two peak outriggers 5 and 6 suspended from the upper end of the jib housing 1. In this movement the outriggers 5, 6 are therefore extracted from the three telescopic parts 2, 3, 4. The speed of this movement can be adjusted over a wide range by adjusting the exhaust valve of the hydraulic cylinder 8. At the end of the movement the upper rim of the telescopic part 4 has reached a predetermined position relative to the lower ends of the outriggers 5, 6. Furthermore during this movement a frame 27 fixed to the upper end of the jib housing 1 prevents the head-stay cable 25 from being pulled downwards into the jib housing 1.

The two peak outriggers 5, 6 are rotatably mounted on an outrigger foot 15. When the telescopic parts 2, 3, 4 have reached the lower limit of their travel the outrigger foot 15 is locked to the upper end of the telescopic part 4. It should be observed that the outrigger foot 15 has a guiding tube 24 which slides over a machined outer surface of the cylinder 8, the outrigger foot 15 being prevented from rotating relative to the telescopic parts 2, 3, 4 for example by a key in a groove.

In the next jib extension stage, hydraulic liquid is admitted to the cylinder 8. Consequently the cylinder 8 lifts the three telescopic parts 2, 3, 4 and the outriggers 5, 6 until an upper rim 16 of the telescopic part 4 has moved past spring loaded catches 17 which are fixed to the upper edge of the jib housing 1, as shown in FIGS. 4a and 4b. In the next stage hydraulic liquid is again exhausted from the cylinder 8. Consequently the two telescopic parts 2 and 3 move downwards, leaving the telescopic part 4 suspended from the upper edge of the jib housing 1. It will be observed that the upper rim 16 of the telescopic part 4 extends radially outwards, at least where it engages with the spring loaded catches 17, so that its diameter is nearly as great as the internal diameter of the jib housing 1, although of course the diameter of the main part of the telescopic part 4 is less than that of the next telescopic part 3. A sufficient clearance remains, however, between the rim 16 and the jib housing 1 to allow the telescopic part 4 freedom of movement in the jib housing 1.

During this downward movement of the telescopic parts 2 and 3 the telescopic part 4 is extracted from the interior of the telescopic part 3, the movement continuing until the lower end of the telescopic part 4 is finally locked to the upper end of the telescopic part 3. In the next stage of jib extension hydraulic liquid is once more admitted to the cylinder 8, moving the telescopic parts upwards, in the manner already described, after which the telescopic part 2 is lowered again.

The parts are now in the positions shown in FIG. 6. After locking the lower end of the telescopic part 3 to the upper end of the telescopic part 2, the cylinder 8 is extended once more, moving the telescopic part 2 upwards as far as the position shown in FIG. 7. In this position the telescopic part 2 projects only part of the way out of the top end of the jib housing 1, leaving the lower end of the telescopic part 2 still located a distance U below the upper edge of the jib housing 1, as shown in FIG. 7. This is necessary because in the illustrated example both the telescopic part 2 and the jib housing 1 are of frame construction with frame mem-

bers of light tubing. In this position the lower end of the telescopic part 2 is locked to the jib housing 1. The example of the crane jib in accordance with the invention shown in the drawings has now been extended to its maximum length, although this length can of course be varied over a wide range by providing different numbers of telescopic parts.

The telescopic jib may however if desired be only partly extended. This can be done in various ways. For example the jib can be used with only the peak outriggers 5, 6 extended, or it can be used with the outriggers 5, 6 and the telescopic part 4 extended, or with the outriggers 5, 6 and the two telescopic parts 3 and 4 extended. Alternatively if desired a reduced jib extension can be obtained by extending the telescopic part 2 containing, retracted within it, the telescopic parts 3, 4 and the outriggers 5, 6. Finally the jib can be used after extending the telescopic part 3 with, retracted within it, the telescopic part 4 and the outriggers 5, 6. This last arrangement allows the jib to take a particularly high load.

When the crane jib is used with telescopic parts retracted within each other, the retracted telescopic parts are locked together.

During the operations of extending and retracting the jib the telescopic parts 2, 3, 4 are guided, as is the outrigger foot 15, on the machined outer surface of the cylinder 8, rotation being prevented, instead of on the surfaces of the frame members. The cylinder 8 is of much more rigid construction than the comparatively thin frame members which, in this example, are of light tubular construction. There is a considerable clearance between the telescopic parts 2, 3, 4 and consequently there is little risk of the paint on the parts being damaged. Lubrication of the telescopic parts is simpler, than with conventional telescopic crane jibs. Instead of extending over the entire length of each longitudinal frame member, the surfaces which have to be lubricated are limited to the outer surface of the cylinder 8. Lubrication is therefore considerably simplified.

Before each movement extending the jib, the telescopic parts 2, 3, 4 and the outriggers 5, 6 are locked together end to end at four locations by means of locking devices of the kind shown in FIGS. 8 and 9. Each locking device consists of a tube 20 fixed to the lower end of the telescopic part 4 or 3, or fixed to the outrigger foot 15, and a tube 30 fixed to the upper end of the telescopic part 2, 3 or 4. Each tube 20 contains a bolt 18 and each tube 30 contains a bolt 19. The longitudinal axes of the tubes 20 and 30 are in line with the diagonals of the square cross section of the jib.

In order to minimise the bending stress applied to the bolts 18 and 19, the tubes 20 and 30 are constructed and fixed to the telescopic parts 2, 3, 4 in such a way that the cooperating tubes 20 and 30 are as near to each other as possible when locked together. This is achieved by extending the lower end of the inner telescopic part outwards and extending the upper end of the outer telescopic part inwards, and also by changing the cross section of each longitudinal tubular member of each telescopic part from the tubular shape shown in FIG. 8a to the rectangular shape of equal area shown in FIG. 8b.

FIG. 8 shows a locking device for locking the lower end of the telescopic part 4 to the upper end of the telescopic part 3. A tube 30 fixed to the lower end of the telescopic part 4 contains a bolt 18 and a tube 30 fixed

to the upper end of the telescopic part 3 contains a bolt 19. Fixed to the upper end of the telescopic part 3 there is also a limit stop 31. The arrangement functions as follows:

At the end of the movement when the telescopic part 3 is being lowered into the jib housing 1, the limit stop 31 comes to rest on the surface of the tube 20 of the telescopic part 4, whereupon the bolt 18 is advanced through a short distance, propelled by the piston of a simple pneumatic cylinder or the like. This brings the bolt 18 into the position shown in FIG. 8. Subsequently when the telescopic part 3 is raised a supporting surface 32 of the telescopic part 3 supports the bolt 18.

The two tubes 20 and 30 are of the same diameter, and the two bolts 18 and 19 are of the same diameter and thus the supporting surface 32 can be the inner surface of the tube 30. For this purpose the upper surface of the tube 30 can be cut away. With the bolt 18 resting on the supporting surface 32 the two bolts 18 and 19 are in line with each other. The bolt 19, which has a sloping under-surface 33, can now easily be advanced into a bore 34 in the bolt 18, with the help of a key wedge 22 the surface of which cooperates with the sloping surface 33. A positive locking effect is obtained which is effective in spite of possible manufacturing inaccuracies or the like. For example the two tubes 20 and 30 may not be exactly in line with each other. The bolt 19 is preferably propelled by the same means as is used for the bolt 18.

The locking action is preferably effected in two stages. In the first stage the bolt 18 advances to take compressive forces acting between the two telescopic parts 3 and 4. In the second locking stage the bolt 19 advances, to take tensile forces acting between the telescopic parts 3 and 4. This 2-stage action has the particular advantage that the locking of the two telescopic parts together does not require a very precise controlling of the hydraulic cylinder 8. The tube 20 first makes contact with the limit stop 31 and the bolt 18 advances. When the cylinder 8 subsequently lifts the telescopic part 3, so that the supporting surface 32 rises into contact with the bolt 18, the two telescopic parts are already correctly positioned relative to each other. In conventional locking systems the bolts have to be advanced under load whereas with the arrangement in accordance with the invention, the two bolts 18 and 19 advance free from load. In particular they are not loaded by the weights of the telescopic parts 3 and 4. Actuation of the bolts therefore requires the application of only quite small forces and the bolts and other parts of the locking device suffer little abrasion.

The three telescopic parts 2, 3, 4 are always locked together end to end, that is to say the full length of each telescopic part is utilised. As the three telescopic parts 2, 3, 4 are all of the same length, the locking together takes place each time at the same location in the jib housing 1. At this location there is a platform 23, fixed to the jib housing 1. The cylinder 8 is controlled from the platform 23. The movements of the locking bolts 18 and 19 are also controlled from the platform 23, by means of limit stops which are not shown in detail in the drawing. The platform 23 are also a further platform 28 are also provided with locking bolts 19 in tubes 30, the locking action being as already described for the upper ends of the telescopic parts. The lower end of the telescopic part 2 can be locked selectively either to the upper platform 28 or to the lower platform 23.

In the case of a crane jib the telescopic parts of which are each either extended fully or not extended at all, this arrangement allows the jib to be lengthened or shortened by half the length of a telescopic part.

During the extension of the jib, as soon as the bolts 18 have been engaged, to effect the first stage of the locking action, a warning signal is produced. The signal ceases only when the other locking bolts 19 have engaged, to effect the second locking stage. The bolts 18 and 19 are made still safer by auxiliary safety devices in the form of bolts to prevent inadvertent disengagement, the warning signals being made to cease only after the bolts have been made safe in this way.

In FIGS. 8c and 8d, safety elements with a warning device are illustrated. The safety elements consist of safety bolts 58, which cooperate with a signal horn 61 of the warning device via an actuating pin 59. In FIG. 8d a control system is shown with two valves 62, 63 serving to actuate the signal horn 61, the valves are connected via lines 64, 65 and 66 with the actuation of the lock bolt 18, the signal horn 61, and a pressure medium source 67.

The safety elements and the warning device operate as follows:

When the lock bolt 18 is extended in the first locking stage, the continuously sounding signal horn 61 gives a warning signal. Due to the warning signal, the operator's attention is continuously called to the fact that the safety bolts 58 are not in final position. After the extending of the lock bolt 19 in the second locking stage, the safety bolt 58 is inserted in the position shown in FIG. 8c. Accordingly, the actuating pin 59 is pushed in positively and valve 63 is adjusted, so that the signal horn 61 is cut off. With the signal horn 61 becoming silent, the operators are notified that the safety bolts 18, 19 are secured by the safety bolts 58 against unintended loosening, and hence the hydraulic cylinder 8 of the crane jib can be moved upward.

In order to ensure that locking takes place only if all four bolts 18 are resting on the supporting surfaces 32, the crane jib is first of all positioned, before it is telescopically extended, by means of the telescopic rod device 26, the jib being positioned in an attitude such that the centre of gravity of the extended telescopic parts 2, 3, 4 is not located outside the supporting surfaces 32. This makes it unnecessary to provide special locking bolts and/or to construct the spring loaded catches 17 or the like in any special way in order to prevent the telescopic parts 2, 3, 4 from toppling over.

The lower ends of the telescopic parts 2, 3, 4, and the outrigger foot 15, can be locked to each other, or to the jib housing 1, by means of the bolts 18, as shown for example at Z2 in FIG. 4a. However in this case, as shown in FIG. 10, in contrast to FIGS. 8 and 9, the bolts 18 cooperate with sleeves 35. In FIG. 10 the sleeve 35 is fixed to a telescopic part. Each sleeve 35 has an internal sloping surface or wedge 36 which ensures a firm locking connection, even if the bolt 18 is not precisely in line with the sleeve 35, for transmitting longitudinal shear stresses between the connected telescopic parts.

FIG. 11 shows two telescopic parts 2 and 3 locked together at their upper ends, for example at the location Z1 in FIG. 4a. In this case a nose 39 of the bolt 19 of the telescopic part 3 engages in an opening 37 in the telescopic part 4. The opening 37 has a wedge 38, similar to the wedge in the sleeve 35 and consequently a firm connection is made between the two telescopic

parts, even if the nose 39 is not exactly in line with the opening 37.

The bolt 19 may be somewhat out of line with the opening 37 and similarly the bolt 18 may be out of line with the sleeve 35 under the circumstances shown in FIG. 4a. In this case two telescopic parts, for example the telescopic parts 2 and 3, are locked together, whilst in their retracted positions, at their upper ends, at the location Z1, and also at their lower ends at the location Z2. Under these circumstances misalignment can occur due to the considerable distance a between the two locking locations Z1 and Z2. In order to obtain a particularly firm lock, capable of transmitting longitudinal shear stresses between the telescopic parts 3 and 4, after they have been telescoped together, a device is provided for thrusting the nose 39 of the bolt 19 firmly against the wedge 38 in the opening 37. The device consists of a thrust pin 40 which is thrust against the upper surface of the nose 39 by a hydraulic cylinder 41 acting through a wedge 42. To release the thrust pin, the piston rod is retracted into the cylinder 41 by a return spring.

When the two telescopic parts 2 and 3 are in their fully retracted positions they can both be locked to the jib housing 1 as indicated in FIG. 4a. The lower end of the telescopic part 2 is locked to the jib housing 1 at the location Z3. The upper end of the telescopic part 3 is locked to the jib housing 1 at the location Z4. The locking arrangement at the location Z3 is similar to that at the location Z2, using the locking bolts 18 in the lower end of the telescopic part 2. The locking device at the location Z4 is shown in FIG. 11a. Two further locking bolts 47 and 48 are used. The locking bolt 47 is housed in the tube 30 which houses the locking bolt 19, at the upper end of the telescopic part 3. The locking bolt 47 has a nose 50 which has a sloping surface. The nose 50 engages in an opening 51 in the wall of the jib housing 1, the opening 51 having a wedge 52 which cooperates with the nose 50 to give a firm locking effect similar to that produced by the wedge 38 in FIG. 11. The sloping surface of the nose 50 which cooperates with the wedge 52 is a lower surface of the nose 50. The upper surface of the nose 50 also has a sloping surface. This cooperates with a sloping surface of the locking bolt 48. To lock the device, a piston 49 thrusts the locking bolt 48 inwards into firm contact with the sloping upper surface of the nose 50, thrusting the nose firmly downwards against the upper surface of the wedge 52. This gives a firmly locked engagement between the telescopic part 3 and the jib housing 1.

In FIG. 12 the telescopic crane jib is indicated at 43 incorporated as part of a mobile crane. In this example the telescopic jib 43 is stabilised by a head-stay cable 45. A stay cable for the outriggers is shown at 44 and a hoisting cable is shown at 46. On the left in FIG. 12, next to the telescopic jib, a bending strain diagram 54 represents the bending of the jib out of the force plane, after allowing for the influence of the head-stay cable 45. The resulting bending moment curve is shown at 55. From these two curves it can be calculated that the tensile stress in the jib due to the bending load is largely compensated for by the super-imposed compressive stress. The residual tensile stress is taken by the locking bolts 19 which lock the telescopic parts together.

FIG. 13 shows a further example of the invention, in which a crane jib 56 is surmounted by a peak jib 57

which is telescopically extensible in the same way as is the crane jib 43.

I claim:

1. In a telescopic crane jib including an axially elongated jib housing, a plurality of axially elongated individual telescopic parts selectively displaceable between a fully retracted position with all of said parts within said housing and a number of extended positions and during the extending and retracting operations said jib housing and telescopic parts are arranged approximately vertically, and means for positively locking said telescopic parts together in the extended positions, wherein the improvement comprises that each said telescopic part comprises a base at its lower end extending transversely of its elongated direction, a rim at its upper end extending transversely of its elongated direction, and sides extending in its elongated direction between said base and said rim, said sides of said telescopic parts being disposed in spaced relationship so that there is no mutual guiding between said telescopic parts, said positive locking means being located in said base and said rim of said telescopic parts and when said telescopic parts are interconnected in the extended position, said base of the upper said telescopic part is located in the same plane with said rim of said lower telescopic part so that there is no overlapping of said telescopic parts in the extended position, said jib housing having a length at least equal to twice the length of each of said telescopic parts, and releasable catch means located at the upper end of said jib housing and arranged to hold at least one of said telescopic parts in a position within said housing spaced upwardly from the lower end of said housing.
2. In a telescopic crane jib, as set forth in claim 1, wherein said telescopic parts include a lowermost telescopic part and at least one other said telescopic part arranged to extend outwardly from said lowermost part in the extended position, and in the retracted position the base of said lowermost telescopic part supports the bases of said other telescopic parts positioned above it.
3. In a telescopic crane jib, as set forth in claim 2, wherein a cylinder and piston assembly is positioned within said housing interiorly of said telescopic parts with said cylinder fixed to said base of the lowermost said telescopic part and said piston movably displaceable from said cylinder and secured to the lower end of said jib housing, said telescopic parts being slidably displaceable relative to and guided in the longitudinal direction by said cylinder and being secured relative to said cylinder against rotation.
4. In a telescopic crane jib, as set forth in claim 3, wherein said telescopic part and said housing are each formed of a lattice frame construction extending for the full length of said telescopic parts between said base and said rim of each and for the full length of the lateral sides of said housing.
5. In a telescopic crane jib, as set forth in claim 1, wherein said rim of each said telescopic part extends transversely outwardly from the upper end of said sides of said telescopic part and said base of each said telescopic part extends transversely inwardly from the lower end of said sides of said telescopic part, and in the extended position of said telescopic parts said upper rim of the lower one of two adjacent said telescopic parts has an inwardly facing surface juxtaposed to an outwardly facing surface on said base of the upper one of the two adjacent said telescopic parts, the in-

wardly facing surface of said rim and the outwardly facing surface of said base having corresponding tapers extending inwardly in the upward direction of said telescopic parts.

6. In a telescopic crane jib, as set forth in claim 1, wherein two peak outriggers are positioned in the retracted position within said telescopic parts, means pivotally connecting said peak outriggers to said telescopic part located outermost in the fully extended position of said jib, and means for spreading said peak outriggers apart from each other when said outermost telescopic part is extended outwardly.

7. In a telescopic crane jib, as set forth in claim 1, wherein said jib includes peak jib means connected to said telescopic part located outermost in the fully extended position.

8. A crane jib as claimed in claim 1, wherein said releasable catch means includes a plurality of spring-loaded catches.

9. In a telescopic crane jib, as set forth in claim 1, wherein said locking means on said telescopic parts are arranged to transmit compressive forces between the upper end of one said telescopic part and the lower end of the adjacent said telescopic part in the extended condition and also to transmit tensile forces therebetween.

10. A crane jib as claimed in claim 9, wherein said locking means each comprises two bolts, a support, means locating said bolts for sliding movement in alignment with each other and in directions perpendicular to the longitudinal axis of said jib, said two bolts sliding in opposite directions in two adjacent telescopic parts whereby when one of said two bolts has been advanced, said two bolts are accurately aligned with each other by said support and advancement of the other of said two bolts causes said two bolts to engage with each other.

11. A crane jib as claimed in claim 10, wherein said support includes means defining an opening corresponding to the cross section of the one of said two bolts on said adjacent telescopic part, said opening being in line, in the direction of the longitudinal axis of said jib with said one of said bolts, whereby when said one of said bolts has been advanced into a locking position and said adjacent telescopic part moves downwards relative to said support said one of said bolts rests on said support.

12. A crane jib as claimed in claim 11, wherein said one of said bolts on said adjacent telescopic part which operates with said support has means defining an opening in which the upper of said bolts engages when said other bolt is advanced in the direction of said one bolt to form said second stage locking means.

13. A crane jib as claimed in claim 12, wherein said opening of said bolt of said adjacent telescopic part is a central bore and said other bolt includes a projection directed towards said one bolt, said projection engaging in said bore when the centres of said two bolts are equidistant from said support.

14. A crane jib as claimed in claim 10, further comprising fluid pressure-operated cylinders and means operatively connecting one of said cylinders to each of said two bolts for advancing said bolts.

15. A crane jib as claimed in claim 10, further comprising auxiliary safety devices operatively connected to each of said two bolts.

16. A crane jib as claimed in claim 15, further comprising means for producing a warning signal, means connecting said means for producing a warning signal to said auxiliary safety devices and means for rendering said means for producing a warning signal inoperative when said auxiliary safety devices are operated to lock said two bolts in operative positions.

17. A crane jib as claimed in claim 10, further comprising means for locking said telescopic parts to said jib housing when said telescopic parts are in said retracted positions.

18. A crane jib as claimed in claim 17, wherein said means for locking said telescopic parts to said jib housing includes means for locking said telescopic parts at both their upper and lower ends to said housing.

19. A crane jib as claimed in claim 18, comprising means defining openings in said telescopic parts and in said jib housing, said means including means defining wedge surfaces in said openings, and said bolts engaging said wedge surfaces when advanced into operative positions into said openings, said wedge surfaces compensating for manufacturing tolerances in distances between said locking means at the upper and lower ends of said telescopic parts.

20. A crane jib as claimed in claim 19, further comprising means enabling said bolts to engage in said openings without clearance when said bolts are advanced into said openings with said telescopic parts in said retracted positions.

21. A crane jib as claimed in claim 20, further comprising wedging devices cooperating with said bolts.

22. A crane jib as claimed in claim 21, wherein said wedging devices include thrust pins, means mounting said thrust pins for movement perpendicular to the direction of movement of said bolts, fluid pressure-operated cylinder means and wedge means operatively connecting said fluid pressure-operated cylinder means to said thrust pins for urging said thrust pins one against each of said bolts.

23. A crane jib as claimed in claim 21, wherein said wedging devices each include a further locking bolt, fluid pressure-operated cylinder means for actuating said further bolt and means defining wedge surfaces on said further bolt, said wedge surfaces engaging with one of said two bolts.

24. A crane jib as claimed in claim 10, wherein said telescopic sections are each of rectangular cross section and wherein said bolts extend along diagonals of said rectangular cross section.
